[57] **CLAIM**

The ornamental design for a stackable firewood storage tube, as shown and described.

DESCRIPTION

FIG. 1 is a perspective view of a stackable firewood storage tube, showing my new design;

FIG. 2 is a top plan view thereof;

FIG. 3 is a side elevation view thereof, the opposite side being a mirror image of that shown;

FIG. 4 is a bottom plan view thereof;

FIG. 5 is a front elevation view thereof; and

FIG. 6 is a rear elevation view thereof.

*FIG. 1.**FIG. 2.**FIG. 5.**FIG. 3.**FIG. 6.**FIG. 4.*
